UNITED STATES PATENT OFFICE.

ROBERT WALTER AND ROBERT PETER WALTER, JR., OF ST. LOUIS, MISSOURI.

DESIGN FOR A BASKET.

59,697.

Specification for Design.

Patented Nov. 15, 1921.

Application filed March 25, 1921. Serial No. 455,652. Term of patent 7 years.

To all whom it may concern:

Be it known that we, ROBERT WALTER and ROBERT PETER WALTER, Jr., citizens of the United States, residing at St. Louis, county of St. Louis City, State of Missouri, have invented a new, original, and ornamental Design for Baskets, of which the following is a specification, reference being had to the accompanying drawing, forming a part thereof.

The figure is a side elevational view of a basket, showing our new design.

We claim:

The ornamental design for a basket as shown.

ROBERT WALTER.

ROBERT PETER WALTER, JR.
